Inventor:

Arthur Hough

By Percy H. Moore
Attorney

UNITED STATES PATENT OFFICE.

ARTHUR HOUGH, OF NEW YORK, N. Y.

CONDENSER.

1,312,118.

Specification of Letters Patent. Patented Aug. 5, 1919.

Application filed April 9, 1918. Serial No. 227,468.

To all whom it may concern:

Be it known that I, ARTHUR HOUGH, a subject of the King of Great Britain, residing at New York, in the county of New York and State of New York, have invented certain new and useful Improvements in Condensers, of which the following is a specification.

This invention relates to improvements in condensers, more particularly for nitric acid.

The invention has for its general object increased efficiency of operation over condensers of this general type heretofore known.

The invention also has for its object particularly to facilitate the assembling or putting together of the parts, as well as the disassembling or taking apart of the same, among other things, for compactness in shipping, storage or other purposes.

A further object is to simplify construction, and lessen expense of manufacture, and facilitate transportation.

The invention consists therefore in the peculiarity of the construction and arrangement of parts substantially as hereinafter more fully disclosed and defined by the appended claims.

In the accompanying drawings is illustrated the preferred embodiment of my invention wherein it will be understood that various changes and modifications as to the detailed construction and arrangement of parts may be made, including the substitution of minor subsidiary parts without departing from the spirit or scope of the invention falling within the scope of the claims and in which drawings:

Figure 1 is a partly side elevation and partly sectional elevation of my nitric acid condenser, parts being shown fragmentally;

Fig. 2 is an end elevation of the same;

Fig. 3 is a detached side elevation of one of the removable sections or constituent parts of the inclosure or casing;

Fig. 4 is a side perspective view of one of the removable sections;

Figs. 5 and 6 are individual views, partly fragmental, of the nitric acid receiving or passing pipes, viewed in different angular positions;

Fig. 7 is a detailed transverse sectional view taken as for instance on the line 7—7 of Fig. 6.

In carrying out my invention, I form or

construct a general inclosure or casing 1 of a plurality of sections, parts or members 2, preferably five, detachably assembled or put together preferably as shown, or otherwise, whereby they may be conveniently assembled in setting up the inclosure, as well as disassembled or taken apart with facility, as in shipping or storing the inclosure or casing fragmentally, or sectionally for compactness or economizing space or room, as will be readily appreciated. These sections or members 2 are preferably constructed or provided upon their end portions with meeting-flanges 3, opposed flanges being adapted to face or rest flush with and in contact with each other and being suitably bolted together by nut-equipped bolts 4, said flanges being preferably braced or strengthened by web-formations 5 integral with the inclosure-forming sections and said flanges. Also these inclosure-forming sections have formed in the edges of their end portions arcuate recesses 6 to receive, and to conform to the outline of the nitric acid passing or receiving tubes or pipes 7, as clearly shown, said arcuate recesses also being formed along their outer edges, with flanges 8 preferably in continuation of the flanges 3, intermediately of which flanges 8 and said pipes, is inserted suitable packing 9 for rendering the casing 1 liquid tight, said flanges 3 having upturned and down-turned end portions 10 and 20 respectively to receive, and retain between them the sections against displacement, and to provide for readily guiding said sections to place as the latter are being assembled. The end portions 10 are also preferably provided with dowel pins 21 adapted to seat in corresponding openings 22 formed in the adjacent flanges, as shown in Figs. 3 and 4.

The nitric-acid passing or receiving pipes 7 which as above indicated, are positioned in casing 1 and which are formed in sections and each with an intermediate transversely flattened longitudinally elongated portion 11, have their sections so connected together as to extend tortuously or substantially sinuously through the casing or inclosure, as seen particularly in Fig. 1, to provide for the extended or lengthened passing of the nitric acid therethrough for the effective or thorough treatment or condensation of the acid, as will be appreciated. It will be understood that the cross sectional area of the flattened portions of the pipe

sections is the same as the terminal or end portions thereof thus obviating any retardation in the flow of the nitric acid therethrough. The pipe-sections have oppositely 5 upwardly and downwardly turned cylindrical terminals or end portions 12, 13, said terminals or end-ports interfitting into each other for forming a fluid or vapor tight joint 14 therebetween as seen, particularly in Fig. 1. Suitable packing 23 is 10 preferably employed at the joint 14. The longitudinal elongated transversely constructed portions 11 of the pipes 7 greatly augment the condensation of the acid passing therethrough as is apparent.

Inlet openings 15 are provided at suitable points in the casing or inclosure 1 for the delivery or passing thereinto of the condensing medium, such as water, which may 15 be drawn off from suitable openings 30 at the bottom of the casing.

I claim:

1. A condenser of the type described, including an inclosure comprising a plurality of separable or portable sections, with their meeting edges formed with flanges adapted to provide for the disassociating of said sections and the reassembling thereof, said flanges having portions 25

adapted to guide the superposed sections to 30 place during the reassembling of said sections.

2. A condenser of the type described, comprising an inclosure formed of a plurality of separable sections, with their meeting edges provided with recesses and a sectional pipe positioned to extend substantially sinuously or tortuously through said inclosure and received in said recesses. 35

3. A condenser of the type described, comprising an inclosure and a sectional fluid or liquid receiving or conducting pipe having intermediate its end portions a transversely flattened and longitudinally elongated portion, said pipe extending through said inclosure. 40

4. A condenser of the type described combining an inclosure formed of separable or portable sections with recesses in their meeting edges, a plurality of pipes 50 each formed of a plurality of separable or portable sections and having an intermediate flattened and longitudinally elongated portion, said plurality of pipes being received in said recesses of the inclosure-sections. 55

In testimony whereof I affix my signature.
ARTHUR HOUGH.
